UNITED STATES PATENT OFFICE.

FRANK D. BROWN AND JULIUS H. WERLING, OF HUNTINGTON, INDIANA.

APPARATUS FOR OPENING AND CLOSING DOORS, GATES, &c.

1,110,878.

Specification of Letters Patent. Patented Sept. 15, 1914.

Application filed August 27, 1913. Serial No. 786,991.

To all whom it may concern:

Be it known that we, FRANK D. BROWN and JULIUS H. WERLING, citizens of the United States, both residing at Huntington, in the county of Huntington and State of Indiana, have invented certain new and useful Improvements in Apparatus for Opening and Closing Doors, Gates, &c.; and we do hereby declare the following to be a full, clear, and exact description of the invention, such as will enable others skilled in the art to which it appertains to make and use the same.

The present invention relates to apparatus for opening and closing doors, gates and the like, and consists in the arrangements and combinations of parts hereinafter disclosed and particularly set forth in the accompanying claims.

The invention has for its purpose to provide means for opening and closing doors and gates by persons riding in vehicles without requiring such persons to leave the vehicle, as is now customary.

A further purpose of the invention is to provide an arrangement wherein the door or gate may be opened or closed on either side thereof by a simple manually performed operation, and requiring but little strength to perform; and wherein the complete apparatus will be inexpensive to install and will not readily get out of order.

The invention as disclosed herein is designed especially for operating swinging doors or gates as distinct from the sliding type; and for which latter kind we have designed a special form of apparatus disclosed in our copending application bearing Serial No. 786,992 and executed of even date herewith.

The invention is shown by way of illustration in the accompanying drawings, wherein:

Figure 1 shows the apparatus as applied for operating the doors of an automobile garage or stable. Fig. 2 is a top plan view of the same taken on the line 2-2 of Fig. 1. Fig. 3 is a detail view of the pulley arrangement and associated parts; and Fig. 4 is a detail perspective view of the shaft and door operating connections.

Referring to the construction in further detail and wherein like characters of reference indicate the corresponding parts in the views shown, A and B represent the doors or gates to be operated, and which, in the pres-

ent illustration, represent the doors of a garage or stable C, hingedly mounted at D and E after the usual manner.

A shaft 1 is journaled in the bearings 2 of the supports 3 and 4 comprising pipes or posts fixed in the ground, as shown. A reel or spool 5 is fixedly mounted on the shaft 1, and has secured thereto one end of each of the cords or chains 6 and 7 whose opposite ends are connected respectively to the arms 8 and 9 mounted on the doors A and B (see Fig. 3). The cords or chains 6 and 7 pass over the pulleys 11 and 12 that are journaled in the brackets 13 and 14, and said brackets are in turn mounted on the garage, as clearly illustrated in Fig. 1.

The foregoing described apparatus is adapted for closing the doors A and B when the shaft 1 is rotated to wind the cords or chains 6 and 7 on the pulley 5, i. e. when said shaft is rotated in a counter-clockwise direction.

The means for swinging open the doors to the positions indicated in Fig. 2, consists of a similar pair of cords or chains 15 and 16, having each one end connected to the spool or reel 17 that is fixedly mounted on the shaft 1. The cord or chain 16 has its opposite end secured to the arm 9 mounted on the door B; and the flexible member 15 is connected to the arm 8 of the door A to swing open the latter through the medium of a pulley 18 journaled in the bracket 19 that is in turn mounted on the garage, as shown in Fig. 1.

From the foregoing it will be readily seen that the winding of the chains or cords 15 and 16 on the reel or spool 17 will swing the doors to an open position, during which time the flexible members 6 and 7 will be unwound from the spool or reel 5, and this operation will be reversed when the mechanism is operated to close the doors.

The shaft actuating means consists of a pair of grooved and notched pulleys 20, mounted on either end of the shaft 1 and having engaging therewith each an endless chain 21, whereby the shaft 1 may be rotated in either direction for the purpose aforesaid.

The provision of a shaft operating chain to either side of the doors enables the doors to be opened for passing through and closed when passed through without requiring the occupant of the vehicle to leave the same.

It is obvious that those skilled in the art

may vary the details of construction and arrangement of parts without departing from the spirit of our invention, and therefore we do not wish to be limited to such features except as may be required by the claims.

The word "door" or "doors" as used in the claims is intended to cover gates as well.

We claim:

1. In a device for operating a pair of doors, the combination of a rotatable shaft, means for rotating said shaft in either direction, spaced reels fixed on said shaft, both located on that side of shaft toward which the adjacent door opens, two pulleys suitably mounted adjacent to the doors when in closed position, two brackets, mounted one on each door and at right angles to faces of the doors, a third pulley suitably mounted near the door opposite said shaft when said door is in open position, a pair of flexible members connected to a reel, coöperating with said brackets and said two pulleys to close the doors, a third flexible member connected to a second reel and coöperating with the bracket on the adjacent door to open

said adjacent door, a fourth flexible member connected to said second reel, coöperating with said third pulley and the bracket on the opposite door, to open said opposite door.

2. In a device for operating a door, the combination of a rotatable shaft, rotating means for said shaft, spaced reels fixed on said shaft, both located on that side of the shaft toward which the door opens, a pulley suitably mounted adjacent to said door when closed, a bracket mounted on said door and at right angles to its face, a flexible member connected to a reel, coöperating with said pulley and said bracket to close the door, a second flexible member connected to a second reel coöperating with said bracket to open the door.

In testimony whereof, we affix our signatures, in presence of two witnesses.

FRANK D. BROWN.
JULIUS H. WERLING.
